UNITED STATES PATENT OFFICE.

ARTHUR WELLS MINNEY, OF LOS ANGELES, CALIFORNIA.

BEATER.

Application filed June 14, 1923. Serial No. 845,366.

To all whom it may concern:

Be it known that I, ARTHUR W. MINNEY, a citizen of the United States, and a resident of Los Angeles, in the county of Los Angeles and State of California, have invented certain new and useful Improvements in Beaters, of which the following is a specification.

This invention relates to beaters and is 10 more particularly directed to a beater adapted for use in the preparation of articles of food.

An object of the invention is the provision of a strong, durable and easily cleanable beater or mixer which may be readily assembled or disassembled.

A further object of the invention is the provision of a beater or mixer in which all the parts that are susceptible to wear are 20 enclosed, so that the ingredients which are being mixed or beaten may not come in contact with said parts.

Another object of the invention is the provision of a compact sanitary structure 25 which is positive in its action and so constructed that all the moving parts of the mixer are spaced relative to each other that a minimum amount of wear will be had.

Other objects and advantages will become apparent during the course of the following description.

The invention is illustrated by way of example in the accompanying drawings, in 35 which,

Figure 1 is a view in perspective of the mixer with parts broken away to disclose the internal beater,

Figure 2 is a horizontal sectional view 40 of the same, and

Figure 3 is a vertical sectional view showing the parts in operative position.

Referring to the drawings, 1 designates a cylindrical container having a flat circular bottom 2. The bottom portion is provided with a central perforation from which is upwardly extended a vertical sleeve 3, formed integrally with the bottom of the container.

50 The upper end of the container 1 is open, and adapted to be closed by a cover 5, having an annular depending flange 6 located within the container and in close contact with the inner wall of the container, and 55 a lateral flange 7 adapted to rest upon the upper peripheral edge of the container 1.

The flange 6, snugly fitting the inner wall of the container 1, prevents loss of the ingredients when the beater is in operation.

A handle 8 is mounted centrally of the cover 5. At diametrically opposite points and riveted to the inner face of cover 5 and adjacent its peripheral edges are stationary beaters 9 which are formed integrally with the bar 10. The bar 10 is provided with a right angular flange 4 which is riveted to the cover 5. Pointed stationary beaters 11 are located on opposite sides of the fixed sleeve 3.

A cylindrical shaft 11 is rotatably mounted within the sleeve 3 and has a bearing 12 at the upper extreme end of said sleeve. The bearing is separate from the sleeve and is of such diameter that when forced into the upper end of the sleeve it will remain in a fixed position. A second bearing 13 is mounted in the lower end of the sleeve 3 and is provided with a flange 14 resting on the hub 15 of a beveled gear 16 which is pinned to the shaft 11 below the bottom of the container 1. The flange 14 of said bearing is in engagement with the bottom of the container, while the bearing 13 is forced into immovable relation with the sleeve 3. A second sleeve 17 telescopes the sleeve 3 in spaced relation and is provided with an enlarged closed end 18 having a rectangular passage 19 through which is inserted the squared end 20 of the shaft 11. The member 18 is spaced from the bearing 12 since the cylindrical portion of the shaft 11 extends slightly beyond the bearing 12 and forms with the squared portion 20 a shoulder spaced from the bearing 12 and upon which the member 18 is seated.

The upper end of the shaft 11 which projects beyond the enclosed end of the sleeve 17 and the member 18 is threaded to receive a winged nut 49 which locks said sleeve to the shaft. The sleeve 17 extends downwardly for a portion of the length of sleeve 3.

At diametrically opposite points on the lower end of the sleeve 17 are integrally formed or otherwise rigidly secured two depending arms 21 and 22. Each arm carries a right angular extension 23 which is directed radially outward from the sleeve 3 and adjacent to the base 2 of the con-

tainer 1. Vertical beaters 24 are formed integrally with or connected to the right angular extensions 23 and are sufficiently spaced from the beaters 9 to pass between said depending stationary beaters rigidly connected to the cover 5, when the shaft 11 is rotated.

A bracket 25, which is of angular formation, has a horizontal member 26 extending radially from the shaft 11 and in engagement with the base 2 of the container 1. A second radial arm 27 in alinement with arm 26 is in engagement with the base of the container. The lower end of the bracket 25 has a lower horizontal arm 28 spaced from the radial arm 27.

A pair of spaced vertical standards 29 and 30 connect the radial arms 27 and 28 together. An auxiliary bracket 31 is integrally formed with the bracket 25 and has two vertical standards spaced from each other. At the lower end of the bracket 31 is integrally formed a horizontal clamping arm 32 carrying the screw 33 provided with a knurled knob 34 for operating the screw. A swivelled disk 35 is adapted to engage the undersurface of a table 36. The table top is clamped between the disk 35 and the arm 28.

The lower end of the shaft 11 is mounted in bearings formed in the angular portion 37 of the bracket 25. A second angular portion 38, which is integrally formed with the bracket 21, is perforated and receives the shaft 11 and maintains the sleeve 39 in position.

The bevelled gear 16 mounted on the shaft 11 below the bearing 13 meshes with a bevelled gear 40 mounted on a shaft 41. The shaft 41 is mounted in bearings in the standards 29 and 30 and extends through the auxiliary bracket 31. The portion of the shaft 39 located within the bracket 31 is provided with a toothed wheel 42 over which a chain 43 is directed which likewise embraces a second toothed wheel 44 mounted on a shaft 45. Said shaft is mounted in bearings at the upper ends of bracket 31. A crank 46 rigidly connected with said shaft, is adapted to operate the same.

A circular rest 47 is rigidly secured to or integrally formed with the horizontal radial arms 26 and 27 of the bracket 25 and is adapted to form a support for the base 2 of the container 1. At diametrically opposite points on horizontal radial arms 26 and 27 are formed perforations which are adapted to receive lugs 48 for maintaining the container 1 in position.

It is particularly pointed out that all of the operating parts which are enclosed between the sleeves 3 and 17 are spaced from each other as shown in Figure 3 to prevent wear of said parts when the beater is in operation.

The operation of my device is as follows:

The beaters 24 are positioned within the container 1 as shown in Figure 3, with the nut 49 tightened for locking the sleeve 17 to the shaft 11. Whatever ingredients desired to be beaten or mixed are placed within the container when the top 5 is located in position with the beaters 9 depending from said top and projecting into the container. The crank 46 is then operated, operating the shaft 45, chain 43, gears 44 and 42, shaft 41, gears 40 and 16 and shaft 11. Rotation of the shaft 11 causes rotation of the sleeve 3, arms 23 and the beaters 24.

The annular depending flange 6 of the cover 5 co-operating with the lateral flange 7, prevents loss of any of the ingredients from the mixer when the same is in operation.

It will be noted that the beaters 24 cut through the ingredients and pass between the stationary paddles 9 whereby the ingredients in the container 1 are thoroughly beaten or mixed. This beater or mixer will beat or mix eggs, frostings, coatings, mayonnaise, cake-dough, pancake-dough, custards, sauces, whipped cream, egg-nogg milk-shake, batters of all kinds, and in fact anything except stiff bread-dough.

When it is desired to remove the beaten ingredients of the container, top 5 is raised with beater 9. Nut 49 is then unscrewed. The container may be freely lifted off its position on the shaft 11. The removal of nut 49 also permits a release of the movable beaters 24 formed integrally with sleeve 17.

It is to be noted that the removal of the single nut 49 provides for a ready dismantling of the beater for discharge of the beater ingredients and for cleaning purposes.

What I claim is:

1. In a beater or mixer, a clamping bracket, an open-ended container adapted to be mounted on the bracket, a cover having a depending flange adapted to be mounted on the open end of the container, stationary beaters depending from the cover removable therewith and projecting into the container, a fixed sleeve rigidly connected centrally of the base of the container and projecting upwardly into the same, a shaft having one end squared and its other end mounted for rotation in the bracket and extending lengthwise of and beyond the sleeve, a bearing on the end of the sleeve for said shaft, a rotatable sleeve having one end closed mounted on the squared end of the shaft and spaced from the fixed sleeve, the closed end of the sleeve having a squared opening adapted to receive the squared end of the shaft, arms rigidly connected with the rotatable sleeve and depending therefrom and having right angular extensions radiating outwardly and located adjacent the bottom of the container, vertical beat-

- ers rigidly connected with said right angular extension and adapted to be moved between the stationary beaters depending from the cover, means connected with the shaft 5 for rotating said shaft and the movable beaters, and means for locking the movable beaters and the container in position relative to the shaft and bracket.
2. In a beater or mixture, a clamping bracket having horizontally radiating arms, a ring connected to the ends of said arms and provided with diametrically disposed perforations, a container mounted on the bracket and supported at its base by the ring 10 and radiating arms, lugs at diametrically disposed points on the base of the container adapted to be seated in the perforations in the ring.
3. In a beater or mixer, a clamping bracket, an open-ended container adapted to be mounted on the bracket, a cover having a depending flange adapted to be mounted on the open end of the container, stationary beaters depending from the cover removable 15 therewith and projecting into the container, a fixed sleeve rigidly connected centrally of the base of the container and projecting upwardly into the same, a shaft having one end squared and its other end mounted for rotation in the bracket and extending lengthwise of and beyond the sleeve, a bearing 20 on the end of the sleeve for said shaft, a rotatable sleeve having one end closed mounted on the squared end of the shaft 25 and spaced from the fixed sleeve, beaters connected with the rotatable sleeve and mov-
- able between the stationary beaters, means for rotating the shaft, and means for locking the rotatable sleeve and container in position relative to the shaft and bracket. 40
4. In a beater, a clamping bracket, an open-ended container removably mounted on the bracket, a cover for the container carrying depending stationary beaters removable with the cover, a rotatable shaft projecting into 45 the container, vertical beaters mounted on the shaft for rotation in the container and projecting upwardly between said stationary beaters, a single means for removably locking the vertical beaters and the container against displacement from its bracket, and means connected with the shaft for rotating said shaft and the movable beaters. 50
5. In a beater, a clamping bracket, an open ended container removably mounted 55 on the bracket, a cover for the container carrying depending stationary beaters removable with the cover, a rotatable shaft projecting into the container, a bearing for the shaft projecting into the container and 60 forming a seal against the material to be beaten in the container, vertical beaters mounted on the shaft for rotation in the container and projecting upwardly between said stationary beaters, a single means for 65 removably locking the vertical beaters and the bearing and likewise the container, against displacement from the bracket, and means connected with the shaft for rotating said shaft and the movable beaters.

ARTHUR WELLS MINNEY.
